UNITED STATES PATENT OFFICE

CARLON P. DUBBS, OF WILMETTE, ILLINOIS, ASSIGNOR TO UNIVERSAL OIL PRODUCTS COMPANY, OF CHICAGO, ILLINOIS, A CORPORATION OF SOUTH DAKOTA

PROCESS AND APPARATUS FOR CONVERTING OIL

Application filed March 30, 1921, Serial No. 456,812. Renewed March 15, 1928.

This invention relates to improvements in a process for converting oil and refers more particularly to an improved process in which the carbon is effectively eliminated from the expansion chambers by its conversion in the chamber into a gas, thereby avoiding the necessity of the separate removal of the carbon from the chamber; to provide a process in which the gas generated may be collected and stored or may be directly used in the system as fuel or for other purposes in the operation of the process with resulting economy in fuel, labor and time; to provide a process which may be operated continuously and one which may be economically used to convert the oil by utilizing products otherwise drawn off as waste or requiring separate handling or treatment; to provide an apparatus by means of which this process may be effectively carried out and, in general, to provide a process and apparatus of the character referred to.

Fig. 1 is a side elevation of the apparatus with parts omitted and parts in section.

Fig. 2 is a plan detail of the expansion chambers and superheater.

Fig. 3 is a modified form of expansion chamber which is used without a superheater as shown in Fig. 1.

Referring to the details as shown in the apparatus in Figs. 1 and 2—the raw oil from any convenient source is introduced through the inlet line 1 controlled by the valve 2 to the top of a dephlegmator 3. This dephlegmator is of common type filled with fragments of broken material which serves to separate the oil as it courses down through the dephlegmator and subject greater quantities of the oil vapors rising through the dephlegmator to the cooler raw oil medium. The dephlegmator is fitted with a pyrometer 4 or similar temperature recording means and a pressure gauge 5. The raw oil, with what condensate it may collect from the vapors arising in the dephlegmator, is drawn off through the line 6, which is controlled by a valve 7. This line directs the oil to a pump 8 or it may be by-passed through the line 9 regulated by the valve 10. In either case the charging stock passes through a line 10a to

cracking tubes 11 mounted in a furnace 12 preferably heated by a gas burner 13. The oil, being heated to a cracking temperature in the heating tubes, passes through the transfer line 14 in which is interposed a pyrometer 55 15 and a pressure gauge 16. The transfer line 14 branches through three connecting lines 17, 18 and 19 to three expansion chambers 20, 21 and 22 respectively. These expansion chambers are preferably vertical in 60 form lined with refractory material as shown at 23, such as fire clay or fire brick. Each expansion chamber is fitted with the residuum draw-off line 24 controlled by a valve 25. The chambers are identical in construction and 65 are adapted to be cut into the system as desired by means of the valves 26, 27 and 28 in the lines 17, 18 and 19.

In the bottom of each of the chambers are fitted collapsible grates 29 operated by an 70 adjusting handle 30. The function of the alternate chambers is the operating of one as an expansion chamber while the other is being operated as a gas producer. Describing first the operation as an expansion chamber,—the heated oil passing through the transfer line 14 is directed by the secondary connecting line 19 to the expansion chamber 22. As shown in Fig. 1, the chambers are heavily lagged as shown at 31 to prevent the 80 loss of heat through radiation. From whichever expansion chamber may be in operation as a conversion chamber, the cracked oil vapors are released and rise into the vapor draw-off lines 32. Each chamber is fitted 85 with a similar draw-off line controlled by valves 33 connecting to a common header 34. A single lead 35 controlled by a valve 36 directs the oil vapor to the bottom of the dephlegmator in which it is dephlegmated by 90 being brought into intimate contact with the incoming raw oil. The dephlegmated vapors pass out from the top dephlegmator through the line 37 to a water condenser 38, the distillate being collected in the receiver 39. A 95 gas line 40 controlled by a valve 41 directs the uncondensable gas to the gasometer 42 through a riser 43 regulated by a valve 44 or it may be conducted to the gasometer 45 through the line 46 controlled by a valve 47. 100

The gasometer 42 has a lead 48 regulated by a valve 49 through which the incondensable gas is passed into a line 50 leading back to the gas burner 13. The valves 51 and 52 are 5 interposed in this line. An extension of the gas line 50 leads to the second gasometer 45 so that a mixture of incondensable gas and water gas may be directed to the burner 13. This prior explanation of the cracking operation 10 describes the process when using the chamber 22 as an expansion chamber, the other two chambers 20 and 21 being cut out of the system by closing the valves 26 and 27 and the valves in the vapor draw-off lines. 15 Describing now the mode of using the expansion chambers as gas generators, when a sufficient collection of carbon is obtained in one of the expansion chambers to cause it to be ineffective as an expansion chamber, the 20 chambers. This chamber with the carbon the valves previously mentioned, simultaneous with the cutting in of one of the other chambers. This chamber with the carbon deposition therein is then subjected to an air 25 blast through the compressed air line 53. Air being supplied to the carbon, which is at high temperature, immediately causes the temperature in the expansion chamber to rise until it is at the proper temperature for the 30 production of the desired gas. At this point steam is introduced through the steam line 54 and the air supply discontinued. During the introduction of the air the inert gases formed pass up through the expansion chamber 35 and out through a duct 55 regulated by a valve 56. This duct leads into the bottom of a superheater 57 and during the admission of air to the expansion chamber, which has now become a gas generator, the top vent 40 pipe 58 of the superheater is opened by removal of the cap 59. As soon as the chamber or generator has reached the temperature necessary for the generation of gas, steam is introduced and the vent pipe 58 closed. It is 45 understood during this mode of operation that the valve 60 in the lower duct 61 is closed. The water gas formed by the decomposition of the steam in contact with the incandescent carbon takes a similar course as that of the 50 inert gases through the duct 55 and into the bottom of the superheater 57 where it may be enriched by the carburization with oil through the jet 62 and further addition of air through compressed air pipes such as that 55 shown at 63 positioned at various heights on the superheater. A pyrometer 64 is inserted into the superheater near its top to ascertain the temperature of the gas in that region.

From the top of the superheater the water gas passes out through the line 65 and is bubbled up through a body of water in the tank 66 from which it is directed through a line 67 to the gasometer 45. A draw-off line 68 directs the water gas through a pump 69 65 to a header 70 from which it may be intro-

duced into the bottom of any one of the expansion chambers or gas generators through separate lines 71 controlled by valves 72. The gas may be introduced to the separate chambers only when they are being used as expansion chambers in the conversion of the oil to aid in keeping the carbon in suspension by agitating the residual product and also to promote cracking and evaporation. It also helps to control the porosity of coke or carbon burned in the chamber. When the carbon has collected to an amount that the introduction of the gas in the bottom of the chamber does not effectively reach the oil body, the valve 72 may be closed and the gas 75 directed to an upper header 73 through a line 74 and introduced in the upper part of the chambers through lines 75 regulated by valves 76.

To return to the production of the gas 80 from the carbon—in one of the expansion chambers, when used as a gas producer or generator, as the steam is introduced to the lower portion of the chamber used in this connection the heat taken up by the steam 85 in its decomposition will rapidly cool the carbon body. It is advisable for this reason to introduce steam intermittently with air and at times reverse the passage of air and gas through the generator in order to procure the most efficient operation. To accomplish this result, duplicate steam and air pipes 77 and 78 similarly arranged as the air and steam pipes 53 and 54 are positioned in the top of the generator. To reverse the 90 direction of the air and gas the valve 56 in the duct 55 is closed and air is introduced through the compressed air pipe 78. The valve 60 in the duct 61 is at this time open and the cap 59 in the vent pipe 58 in the 95 top of the superheater is then removed. When the carbon body has reached the proper temperature, which may be ascertained by suitable recording devices, the air is shut off and steam introduced. During the introduction of the steam through line 77, the cap 59 is replaced and the gas directed to the 100 gasometer 45, as explained. In both of the ducts 55 and 61, which have separate connections to each of the expansion chambers, 105 are small vent lines 79 controlled by valves 80. By keeping an ignited flame burning at all times at the top of the vent pipe 79, the operator is able to ascertain the character 110 of the gas produced in the generator. 120

In producing gas in this manner where carbon is permitted to collect in a heavy, sludgy body, as it may under certain operating conditions in these expansion chambers; high air pressure may be used to penetrate 125 the carbonaceous body. To facilitate the passage of air and steam through this carbon body, it may be advisable to place in the chambers quantities of broken fragments of ceramic material to keep the carbon body in 130

divided form and permit the passage of air and steam more freely therethrough. In the production of gas in this manner air is introduced when its need is indicated by the 5 temperature of the coke or carbon. Then when through the introduction of the air the temperature is raised to a proper point steam is reintroduced to generate the gas.

In the modified form of construction 10 shown in Fig. 3 the use of the superheater is omitted, the transferred liquid being introduced to the expansion chamber or gas generator 81 through the inlet line 14. It will be understood that such chamber, shown at 81, 15 may be mounted in the system in pairs or as three units as shown in Fig. 2, the connections to the system being similar to those in Fig. 1. The carbon will collect in the chamber and when it is changed over to be used as a 20 generator, air is injected through the compressed air line 82 controlled by valves 83 and 84. During the injection of the air through the bottom compressor pipe, the pressure tight cap 85 is removed as is also a slidable 25 valve cap 86. The difference in the caps is shown by the construction, the valve 85 serving to cover the top vent when the chamber is being used as an expansion chamber and is bolted to the top flanges of the chamber. These flanged portions are so built that the excessive heat from the gases will not contact with the facings of the flanged portions. When the carbon in the chamber has 30 been brought to the required temperature, 35 the slidable cover 86 is pushed into place over the top of the generator effectively preventing the escape of the generated gas. At this juncture superheated steam is introduced through the lower pipe 87 and the air shut off. The gas is directed out through the 40 draw-off line 88 controlled by the valve 89.

In reversing the travel of the air and gases in the gas generator the valve 84 is closed and the air directed through the vertical 45 line 92 to the upper gas line 88. The valve 89 in this line being open, the air is introduced into the upper part of the converter and as the cap prevents its being short-circuited directly to the chimney the air passes 50 down through the carbon body and thence through the secondary flue 93 from which it is directed to the stack 94. When the carbon has been raised to the temperature necessary 55 to produce water gas, steam is then introduced through a superheated steam jet 95 and the secondary flue 93 closed by a valve 96 therein. At this time the air valve 83 in the line 82 is closed and the valve 84 opened simultaneously with the closing of the valve 89. 60 The travel of the steam through the heated carbon forms the combustible gas which passes out through the valve 84, thence through the vertical line 92 and out through the line 88 through a 65 water tank and gasometer as shown in Fig.

1. In this modified form of construction the superheater has been eliminated and the gas directed to a collecting tank or gasometer directly.

Any liquid residual substance collecting in 70 the expansion chambers during cracking operation may be eliminated by draw-off lines 24 controlled by valves 25.

Through control of pressure and temperature conditions in the circulation of the reflux from the system the deposit of the carbon may be localized in the expansion chamber and there conveniently used for conversion into gas without interruption of the process otherwise necessitated through the accumulation in the heating zone or elsewhere. The gas produced by the method herein set forth may be either water gas, producer gas or inert gas or mixtures thereof according to 80 the method of operation.

I claim as my invention:

1. A process for converting oil, consisting in heating the oil to a cracking temperature in a heating zone, passing the heated oil to alternate expansion chambers and there removing the generated vapors, permitting the collection of carbon in the chamber used in the cracking system, subsequently cutting out a carbonized chamber and generating gas therein by introduction of air and steam thereto, and simultaneously cutting into the cracking system one of the alternate expansion chambers into which the oil is diverted and in introducing the gas produced from the precipitated carbon to assist in converting oil introduced to the system.

2. A process for converting oil, consisting in heating the oil to a cracking temperature in a heating zone, successively directing the oil to alternate expansion chambers, cutting each chamber from the cracking system when a substantial body of precipitated carbon has collected therein and simultaneously cutting in an alternate chamber, introducing air and steam to said isolated chamber to form water 100 gas, collecting said gas and returning it to the expansion chambers to assist in the conversion of oil introduced to said chambers.

3. A process for converting oil, consisting in heating the oil to a cracking temperature in a heating zone, successively directing the oil to alternate expansion chambers, cutting each chamber from the cracking system when a substantial body of precipitated carbon has collected therein and simultaneously cutting in an alternate chamber, introducing air and steam to said isolated chamber to form water gas, collecting said gas and the incondensable hydrocarbon gas resulting from the cracking 115 separately, returning the water gas to the expansion chambers and directing the hydrocarbon gas to the furnace.

4. A process for converting oil, consisting in heating the oil to a cracking temperature in a heating zone, successively directing the 120

- oil to alternate expansion chambers, cutting each chamber from the cracking system when a substantial body of precipitated carbon has collected therein and simultaneously cutting 5 in an alternate chamber, introducing air and steam to said isolated chamber to form water gas, collecting said gas and the incondensable hydrocarbon gas resulting from the cracking separately, combining a portion of 10 the gases and directing the mixture to the furnace, and returning regulated quantities of the water gas to the expansion chamber being operated with the cracking system.

5. A combined cracking and gas producing 15 process, consisting in heating petroleum oil to a cracking temperature in a heating zone, vaporizing the cracked oil in expansion chambers, adapted to be cut in and out of the cracking system, permitting the carbon to 20 collect in an expansion chamber during cracking, in discontinuing the feeding of oil to said carbonized chamber, and in consuming the precipitated carbon therein by alternately introducing air and steam into said 25 chamber, forming gases, and in introducing into the oil a portion of the gases so formed to assist in the conversion of the oil.

6. A combined cracking and gas producing 30 process, consisting in heating petroleum oil to a cracking temperature in a heating zone, vaporizing the cracked oil in expansion chambers adapted to be used one at a time under a reduced pressure, isolating a chamber when a substantial carbon body has precipitated therein from oil conversion, producing 35 water gas in said chamber by intermittent introductions of air and steam to said isolated chamber, while operating one of the alternate chambers as an expansion chamber in 40 the cracking system and in introducing gases thus produced into the oil to assist in the conversion of additional quantities thereof.

7. A combined cracking and gas producing 45 process, consisting in maintaining a supply of petroleum oil under cracking conditions of heat and pressure in an enlarged conversion zone, in which carbon separated from the oil during the cracking reaction accumulates, in simultaneously producing gas from the 50 carbon accumulation resulting from the conversion of oil in a second enlarged zone by injecting steam and air to the accumulated carbon in said second enlarged zone, in collecting such gas and in employing portions thereof to accelerate the conversion of the oil in said first enlarged zone, and in taking off converted constituents of the oil from said 55 first enlarged zone.

8. An apparatus for cracking oil and producing gas, comprising means for maintaining a substantial body of oil in an enlarged chamber under cracking conditions of temperature and pressure to cause substantial conversion of the oil and separation of carbon, which accumulates in said enlarged 65

chamber, means for maintaining the oil body in a second enlarged chamber after the accumulation of carbon in the first enlarged chamber has become objectionable, means for injecting steam and air to the accumulated 70 carbon in said first chamber to produce gas, means for introducing predetermined portions of the gas so produced to the oil in said second enlarged chamber, means for collecting the remaining portions of the gas, and means for taking off the products of oil conversion from each of said enlarged chambers. 75
